UNITED STATES PATENT OFFICE

2,329,134

THERMAL SWITCH

Leo R. Peters, Cleveland Heights, Ohio, assignor
to General Electric Company, a corporation of
New York

Application July 1, 1941, Serial No. 400,645

13 Claims. (Cl. 200—113)

My invention relates to thermal switches, and in particular to switches comprising a thermally responsive element actuated by heat generated by a gaseous electric discharge. A species of switches of this type is disclosed in my copending application Serial No. 385,282, filed March 26, 1941, and another species thereof is disclosed in the United States Patent No. 2,280,550, issued April 21, 1942, on the application Serial No. 289,897, filed August 12, 1939, inventor Wayne C. Smitley. This patent and my application are assigned to the assignee of the present application and disclose switches comprising a stationary electrode and a thermally responsive, bimetallic electrode constructed and arranged to extinguish the discharge between said electrodes by closing the gap therebetween when heated by said discharge. On cooling, the bimetallic electrode returns to its original spaced position with respect to the stationary electrode.

These switches are used commercially for controlling the starting of gaseous electric discharge lamps of the positive column type having electrodes which require heating before starting a discharge therebetween. The switch is connected to one terminal of each of the lamp electrodes, and the other terminal of each of said lamp electrodes is connected to a terminal of an alternating current source of commercial frequency. An inductance is connected between a terminal of the source and an electrode terminal. When potential is applied to the circuit, the glow discharge starts in the switch, the gap between the switch electrodes is closed by the flexing of the bimetallic electrode to extinguish said glow discharge and to permit a heavier heater current to flow through the lamp electrodes which are connected in series across the terminals of the current source by the switch. The extinguishing of the glow discharge permits the bimetallic electrode to cool and thus to flex back to its original, spaced position with respect to the stationary electrode, thus breaking the series connection between the lamp electrodes after these have been heated to their operating temperature and impressing across the lamp the transient voltage surge produced by the inductance. If the discharge in the lamp starts, the voltage then across the switch is the operating voltage of the lamp which is appreciably lower than the voltage of the current source.

Obviously, in such circuits the voltage required to start the discharge in the switch (hereinafter called the breakdown voltage of the switch) must be lower than the voltage of the current source and higher than the operating voltage of the lamp

if the switch is to successfully start the lamp without interrupting the operation thereof after it has started. The breakdown voltage of such switches depends upon the ionizable gas used, the pressure of the gas, the work function of the surface of the electrodes and the spacing of the electrodes.

I have observed that the breakdown voltage is frequently too high or too low in spite of the most careful control of the above factors in the manufacture of the switch. I have discovered that the cause of the difficulty is the mounting of the bimetallic electrode with the free end portion thereof in such position with respect to the stationary electrode that the movement of said bimetal electrode in response to changes in ambient temperature changes the spacing of the electrodes which, in turn, changes the breakdown voltage of the switch. For example, when the free end of the bimetallic electrode is spaced a sufficient distance from the stationary electrode to obtain the desired breakdown voltage at an ambient temperature of approximately 25° C., the spacing is considerably less when the ambient temperature is approximately 100° C. and, of course, the breakdown voltage of the switch is lower. Again, in the manufacture of the switch, the practice is to fix the spacing of the electrodes before the switch is sealed. The heating of the switch parts incident to the sealing operation flexes the bimetallic electrode which frequently presses against the stationary electrode with such force that it becomes distorted in shape. On cooling, the spacing of the electrodes is greater than the original spacing thereof and the breakdown voltage of the completed switch is higher than that desired.

An object of my invention is to provide a glow-type thermal switch in which the above difficulties are avoided. Another object of my invention is to provide a thermal switch of the gaseous electric discharge type in which the breakdown voltage is not affected by changes in ambient temperature encountered in use. A further object of my invention is to provide such a switch of simple structure and minimum cost. Other objects and advantages of my invention will appear from the following detailed description thereof and from the appended claims.

I have found that the above objects of my invention are attained when the electrodes are constructed and arranged in such manner that the smallest gap therebetween is not closed nor appreciably changed in size when the bimetallic electrode flexes in response to changes in ambient temperature encountered in the use of the switch.

This gap is called the fixed gap hereinafter to distinguish it from the gap between the electrodes which is closed by the flexing of the bimetallic electrode on the occurrence of a discharge between said electrodes. This last gap is called the contact gap hereinafter. My novel structure is utilized to make the breakdown voltage of the switch independent of changes in the ambient temperature over a predetermined range. The ambient temperature range may be selected to that encountered in the manufacture and the use of the device to avoid the difficulties characteristic of prior switches.

In the drawing accompanying and forming part of this specification, species of glow-type thermal switches embodying my invention are illustrated, in which Fig. 1 is a perspective view of the switch; Fig. 2 is a side elevational, fragmentary view of the stem part thereof; Fig. 3 is a similar view of the stem part of another species of switch; and Fig. 4 is a perspective view of a pair of electrodes constructed and arranged in accordance with the present invention.

The switch illustrated in Figs. 1 and 2 of the drawing comprises a hermetically sealed glass envelope 10 having a re-entrant stem 12 through which current leading-in wires 13 and 14 are hermetically fused or welded. The stem 12 is provided with an exhaust tube 15 through which the envelope is exhausted of air and filled with the desired ionizable gaseous atmosphere during the manufacture of the switch. A U-shaped electrode 18 comprising a thermally responsive, bimetallic element is welded to support 16, such as a nickel rod, connected to wire 14. The free end of said electrode 18 is located between said support 16 and the electrode 17, said free end terminating near the top of the press of said stem 12 and the lower part of the elongated electrode 17. Said electrode 17 comprises a metal rod, such as a nickel rod, connected to said wire 13. A refractory metal contact 19, such as a rod of molybdenum, is welded to the electrode 18 adjacent or at the free end thereof and on the surface thereof facing the electrode 17. The envelope 10 has an ionizable gaseous atmosphere therein, such as argon at a pressure of about 25 mm., helium at a pressure of about 100 mm., or a mixture of helium and 0.01 to 5 per cent argon at a pressure of about 100 mm.

The electrode 18 comprises two strips of metal having different coefficients of linear expansion securely fastened together, as by welding. The inner strip has a greater coefficient of expansion than the outer strip and the free end of the electrode 18 moves toward the electrode 17 with increasing temperature and away from the electrode 17 with decreasing temperature. While I prefer to make the inner strip of a chrome iron alloy and the outer strip of a nickel iron alloy, it will be understood, of course, that other metals or alloys having the desired characteristics may be used when desired. The electrode 18 and the contact 19 are coated with a material of lower work function, such as zinc, after these elements are welded together and before they are mounted in the envelope 10.

The surface of the stem press around the electrode 17 and the support 16 and between these elements has a coating 11 thereon of electrically conducting material such as powdered aluminum. Said coating 11 also covers the lower portion of the electrode 17 and the support 16 adjacent

the surface of the stem press. Said coating 11 is applied to these parts preferably by painting with a mixture of aluminum metal powder, amyl acetate and nitrocellulose lacquer during the manufacture of the switch and before the stem 12 is fused into the envelope 10, as disclosed in my copending application. Said coating 11 forms an electrically conducting path having a higher resistance than the conducting path through the ionized gas and the electrodes 17 and 18 in the completed switch and its function is to maintain the breakdown voltage of the switch substantially the same in the dark and in the light, as explained in my aforesaid copending application.

As best illustrated in Fig. 2, the U-shaped bimetallic electrode 18 comprises a curved portion and two leg portions, one of which is free to move with respect to the other in response to changes in the temperature of said electrode 18. When the bimetallic electrode 18 flexes, the leg portions thereof tend to move in opposite directions and the curved portion changes its degree of curvature. As a result, the gap between the curved portion of the electrode 18 and the inner end portion of the electrode 17 does not close when said electrode 18 flexes in response to increasing temperature and, in fact, this gap is called a fixed gap herein since the change in size thereof, if any, is so small that the effect thereof on the breakdown voltage of the switch is negligible. By making the fixed gap as small or smaller than the gap between the contact 19 and electrode 17 (the contact gap) even when the ambient temperature is as high as approximately 100° C., the breakdown voltage of the switch is determined by the fixed gap at normal temperatures lower than approximately 100° C., and thus the breakdown voltage of the switch is independent of ambient temperature changes encountered in the use of the switch.

The above structure is highly advantageous when the breakdown voltage of the switch changes steeply as the distance between the electrodes changes. Switches filled with argon at a pressure of approximately 25 mm. or helium at a pressure of about 100 mm. have this characteristic and are difficult to manufacture with a desired breakdown voltage when the contact gap rather than a fixed gap determines the breakdown voltage of the switch. My invention permits the use of such gases to obtain switches having a desired breakdown voltage. For example, when the fixed gap of the switch described above is between about 0.12 and 0.5 mm. and the switch is filled with argon or helium at the above pressures, the breakdown voltage is between 130 and 170 volts. Such switches are successfully used in lamp circuits when the voltage of the current source is as low as approximately 185 volts and the lamp operating voltage as high as approximately 120 volts.

The electrode and stem structure illustrated in Fig. 3 of the drawing is similar to that shown in Fig. 2 except for the electrode 17, the inner end of which is prolonged and bent over the top of the curved portion of the electrode 18. The other features of the switch incorporating the structure illustrated in Fig. 3 are the same as those described above in connection with Figs. 1 and 2. The smallest gap between the electrodes 17 and 18, which is about 0.12 to 0.5 mm., is between the top of the curved portion of the electrode 18 and the prolongation 21 of the electrode 17.

A further advantage of the switches described

above is the enhanced heating of the curved portion of the electrode 18 by the glow discharge covering the closely adjacent electrode 17 which speeds up the closing of the contact gap in the operation of the switch.

The electrodes illustrated in Fig. 4 of the drawing are similar to those disclosed in Patent No. 2,280,550, referred to above, and comprises a bimetallic electrode 22 which flexes and moves the cam-like part 23 of the contact 24 against the stationary electrode 25 mounted between the legs of the electrode 22 when the latter is heated by a glow discharge between said electrodes. The electrode 22 is welded to current inlead wire 26, the inner portion 27 of which is bent over to extend parallel to the electrode 25. The portion 27 is then part of the electrode 22. The gap between the stationary electrode 25 and said portion 27 is smaller than the gap between contact 24 and electrode 25 at ambient temperatures as high as about 100° C., and does not change in size in response to changing ambient temperature. Thus the breakdown voltage of a switch incorporating this structure is independent of changes in the ambient temperature encountered in use.

The sealed, vitreous envelope and the stem part of the switch illustrated in Fig. 4 have been omitted for simplicity of illustration. As disclosed in Patent No. 2,280,550, when the electrodes 25 and 22 have a material of lower work function, such as magnesium, thereon and the sealed envelope contains a gaseous atmosphere consisting of a mixture of neon and about 0.1 to 5 per cent argon at a pressure of approximately 40 mm., the breakdown voltage of the switch is about 75 volts. This switch is useful in circuits comprising a 110 to 120 volt current source and a lamp having an operating voltage of about 65 volts.

Other means for obtaining a fixed gap between the electrodes may be used, when desired. In the structure illustrated in Fig. 4, for example, the straight part of the contact 24 may be spaced a smaller distance from the stationary electrode 25 than the surface of the cam-like part 23 at ambient temperatures encountered in use, or a plate so spaced may be welded adjacent the center of the stationary electrode 25 and facing the leg portion of the electrode 22 secured to the inlead 26.

When desired, a radioactive material, such as uranium oxide, compounds of thorium or the like, may be used in the switch envelope, to make the breakdown voltage of the switch substantially the same in the dark and in the light as disclosed in the United States application Serial No. 403,572, filed July 22, 1941, which corresponds to British application No. 13,341, filed in England August 22, 1940, inventor Basil N. Clack, or the envelope may contain, or consist in whole, or in part, of uranium glass for the same purpose, as disclosed in the copending application of Basil N. Clack, Serial No. 385,003, filed March 24, 1941, which is assigned to the same assignee as the present application. The coating 11 may be omitted or retained, as desired, when such materials or such glass is used. A quantity of finely divided, radioactive uranium oxide on the inner surface of the end of the envelope opposite the stem end thereof is useful for the above purpose.

Other gases or gas mixtures at desired pressures may be used in the envelope, other materials of low work function may be used on the electrodes and the size of the fixed gap between the electrodes may be changed for the purpose of

obtaining a desired breakdown voltage of the switches described above.

From the foregoing, it is apparent that I have provided a glow-type thermal switch of the type comprising a stationary electrode and a thermally responsive, bimetallic electrode having an end which is free to move with respect to said stationary electrode in response to changes in ambient temperature over a predetermined temperature range without affecting the breakdown voltage of the switch.

What I claim as new and desire to secure by Letters Patent of the United States is:

1. A glow-type thermal switch designed for operation within a predetermined range of ambient temperature, said switch comprising a sealed envelope containing an ionizable gaseous atmosphere and normally spaced, cooperating electrodes including a stationary electrode and a thermally responsive electrode constructed and arranged to make contact with said stationary electrode and thus to extinguish the discharge between said electrodes when heated by said discharge, said electrodes having spaced portions providing a fixed gap therebetween which is smaller than the gap between the contact portions of said electrodes over said range whereby the breakdown voltage of the switch is independent of changes in ambient temperature within said range.

2. A glow-type thermal switch designed for operation within a predetermined range of ambient temperature, said switch comprising a sealed envelope containing argon at a pressure of approximately 25 mm. and normally spaced, cooperating electrodes including a stationary electrode and a thermally responsive electrode constructed and arranged to make contact with said stationary electrode and thus to extinguish the discharge between said electrodes when heated by said discharge, said electrodes having spaced portions providing a fixed gap therebetween which is smaller than the gap between the contact portions of said electrodes over said range whereby the breakdown voltage of the switch is independent of changes in ambient temperature within said range.

3. A glow-type thermal switch designed for operation within a predetermined range of ambient temperature, said switch comprising a sealed envelope containing helium at a pressure of about 100 mm. and normally spaced, cooperating electrodes including a stationary electrode and a thermally responsive electrode constructed and arranged to make contact with said stationary electrode and thus to extinguish the discharge between said electrodes when heated by said discharge, said electrodes having spaced portions providing a fixed gap therebetween which is smaller than the gap between the contact portions of said electrodes over said range whereby the breakdown voltage of the switch is independent of changes in ambient temperature within said range.

4. A glow-type thermal switch designed for operation within a predetermined range of ambient temperature, said switch comprising a sealed envelope containing an ionizable gaseous atmosphere, normally spaced, cooperating electrodes and means for maintaining the breakdown voltage of the switch substantially constant in the light and in the dark, said electrodes including a stationary electrode and a thermally responsive electrode constructed and arranged to make contact with said stationary electrode and

thus to extinguish the discharge between said electrodes when heated by said discharge, said electrodes having spaced portions providing a fixed gap therebetween which is smaller than the gap between the contact portions of said electrodes over said range whereby the breakdown voltage of the switch is independent of changes in ambient temperature within said range.

5. A glow-type thermal switch designed for operation within a predetermined range of ambient temperature, said switch comprising a sealed envelope containing an ionizable gaseous atmosphere, normally spaced, cooperating electrodes and radioactive material, said electrodes including a stationary electrode and a thermally responsive electrode constructed and arranged to make contact with said stationary electrode and thus to extinguish the discharge between said electrodes when heated by said discharge, said electrodes having spaced portions providing a fixed gap therebetween which is smaller than the gap between the contact portions of said electrodes over said range whereby the breakdown voltage of the switch is independent of changes in ambient temperature within said range.

6. A glow-type thermal switch designed for operation within a predetermined range of ambient temperature, said switch comprising a sealed envelope containing an ionizable gaseous atmosphere, normally spaced, cooperating electrodes, current inlead wires for said electrodes and a body of electrically conducting material providing a connecting path between said wires of higher resistance than the path through said electrodes and the ionized gas, said electrodes including a stationary electrode and a thermally responsive electrode constructed and arranged to make contact with said stationary electrode and thus to extinguish the discharge between said electrodes when heated by said discharge, said electrodes having spaced portions providing a fixed gap therebetween which is smaller than the gap between the contact portions of said electrodes over said range whereby the breakdown voltage of the switch is independent of changes in ambient temperature within said range.

7. A glow-type thermal switch designed for operation within a predetermined range of ambient temperature, said switch comprising a sealed envelope containing an ionizable gaseous atmosphere and normally spaced, cooperating electrodes including a stationary electrode and a thermally responsive electrode constructed and arranged to make contact with said stationary electrode and thus to extinguish the discharge between said electrodes when heated by said discharge, said electrodes including a material of low work function and having spaced portions providing a fixed gap therebetween which is smaller than the gap between the contact portions of said electrodes over said range whereby the breakdown voltage of the switch is independent of changes in ambient temperature within said range.

8. A glow-type thermal switch designed for operation within a predetermined range of ambient temperature, said switch comprising a sealed envelope containing an ionizable gaseous atmosphere and normally spaced, cooperating electrodes including a stationary electrode and a thermally responsive electrode constructed and arranged to make contact with said stationary electrode and thus to extinguish the discharge between said electrodes when heated by said discharge, said electrodes being coated with zinc

and having spaced portions providing a fixed gap therebetween which is smaller than the gap between the contact portions of said electrodes over said range whereby the breakdown voltage of the switch is independent of changes in ambient temperature within said range.

9. A glow-type thermal switch designed for operation within a predetermined range of ambient temperature, said switch comprising a sealed envelope containing an ionizable gaseous atmosphere and normally spaced, cooperating electrodes including a stationary electrode and a thermally responsive electrode constructed and arranged to make contact with said stationary electrode and thus to extinguish the discharge between said electrodes when heated by said discharge, said electrodes being coated with magnesium and having spaced portions providing a fixed gap therebetween which is smaller than the gap between the contact portions of said electrodes over said range whereby the breakdown voltage of the switch is independent of changes in ambient temperature within said range.

10. A glow-type thermal switch designed for operation within a predetermined range of ambient temperature, said switch comprising a sealed envelope containing an ionizable gaseous atmosphere and normally spaced, cooperating electrodes including a stationary electrode and a U-shaped, thermally responsive electrode constructed and arranged to make contact with said stationary electrode and thus to extinguish the discharge between said electrodes when heated by said discharge, the curved portion of said U-shaped electrode and the inner end portion of said stationary electrode being spaced and providing a fixed gap between said electrodes, said fixed gap being smaller than the gap between the contact portions of said electrodes over said range whereby the breakdown voltage of the switch is independent of changes in ambient temperature within said range.

11. A glow-type thermal switch designed for operation within a predetermined range of ambient temperature, said switch comprising a sealed envelope containing an ionizable gaseous atmosphere and normally spaced, cooperating electrodes including a stationary electrode and a U-shaped, thermally responsive electrode constructed and arranged to make contact with said stationary electrode and thus to extinguish the discharge between said electrodes when heated by said discharge, the end portion of said stationary electrode being disposed adjacent the mid-part of the curved portion of said U-shaped electrode to provide a fixed gap which is the smallest gap between said electrodes over said range whereby the breakdown voltage of the switch is independent of changes in ambient temperature within said range.

12. A glow-type thermal switch designed for operation within a predetermined range of ambient temperature, said switch comprising a sealed envelope containing an ionizable gaseous atmosphere and normally spaced, cooperating electrodes including a stationary electrode and a U-shaped, thermally responsive electrode constructed and arranged to make contact with said stationary electrode and thus to extinguish the discharge between said electrodes when heated by said discharge, said stationary electrode being disposed between the legs of said U-shaped electrode, said U-shaped electrode having a sta-

tionary portion disposed adjacent the portion of said stationary electrode between the legs of said U-shaped electrode to provide a fixed gap which is the smallest gap between said electrodes over said range whereby the breakdown voltage of the switch is independent of changes in ambient temperature within said range.

13. A glow-type thermal switch designed for operation within a predetermined range of ambient temperature, said switch comprising a sealed envelope containing an ionizable gaseous atmosphere and normally spaced, cooperating electrodes including a stationary electrode and a thermally responsive electrode constructed and

arranged to make contact with said stationary electrode and thus to extinguish the discharge between said electrodes when heated by said discharge, said electrodes having spaced contact portions providing a variable contact gap and other spaced portions providing a fixed gap spaced from and smaller than said contact gap when the ambient temperature is within said range whereby the breakdown voltage of said switch is independent of ambient temperature changes under the condition for which said switch is designed.

LEO R. PETERS.
